UNITED STATES PATENT OFFICE

BERNARD T. LEVEQUE, OF WENHAM, MASSACHUSETTS, ASSIGNOR TO UNITED SHOE MACHINERY CORPORATION, OF PATERSON, NEW JERSEY, A CORPORATION OF NEW JERSEY.

PERFORATING.

Application filed March 15, 1920. Serial No. 365,841.

To all whom it may concern:

Be it known that I, BERNARD T. LEVEQUE, a citizen of the United States, residing at Wenham, in the county of Essex and State of Massachusetts, have invented certain Improvements in Perforating; of which the following description, in connection with the accompanying drawings, is a specification, like reference characters on the drawings indicating like parts in the several figures.

This invention relates to the cutting of stock, and for purposes of illustration is described in connection with the perforation of sheet material such as that used in the manufacture of shoes.

In performing such perforating operations it is usual to operate a hollow die either against a suitable punch block or against a backing strip of paper. If the former is used, the punch block must be frequently refaced or replaced, and the die renewed, otherwise the perforations will not be clean cut, and a machine so operating is noisy and cannot be run at high speeds owing to excessive damage to the punch or punch block or both. With a backing strip of paper, on the other hand, very satisfactory perforating may be done, frequent replacement of the punch is not necessary, and the machine may be run at a higher speed, but the continuous consumption of paper constitutes a never ending expense inherent in this method of perforating, and one which it is desirable to eliminate.

It is an object of the present invention, accordingly, to provide for the satisfactory and high grade perforation of stock without the necessity of frequent renewals or repairs of the punch or punch block and without the use of a backing strip of paper. This invention accomplishes by the use of a cutting element or a pair of cutting elements operated to make a ring-like incision part way through the stock, the severing being completed in any suitable manner as by a current of air. In the illustrated embodiment of the invention the perforating is done by means of a pair of co-operating hollow dies arranged for relative reciprocation to cut the stock from both sides, the relative movement being so controlled that upon their approach the two dies do not quite come together, fluid pressure being thereupon exerted to supply a tearing force to push out from the stock the pill partially formed

by the dies. This pressure may be introduced through one of the hollow dies and will be applied entirely to the surface of the pill which lies inside the incision, the pill being forced out through the other die. A machine so constructed is almost noiseless in operation and is capable of operation at extremely high speed.

It may be noted here that the illustrated machine is shown for purposes of exemplification only, since it is obvious that my invention in its method aspects is not limited thereto and in its machine aspects is capable of other embodiments.

With these and other objects and features in view, the invention will now be described in connection with the accompanying drawings and pointed out in the claims.

Fig. 1 is a side elevation and Fig. 2 a front elevation of a perforating machine in connection with which the invention will be described;

Fig. 3 is a detail cross-sectional view through the dies and fluid pressure cylinder of the machine of Figs. 1 and 2; and

Fig. 4 is a diagrammatic sectional view illustrating the relation of the dies to one another and to the stock at the conclusion of the perforating operation and before the commencement of the separation of the dies.

The illustrated machine is provided with a base 10 from which extends a standard 12 provided with a bearing 14 for the drive shaft 16, the latter being rotated from any suitable source of power as through a pulley 18 and belt 20. Supported by the standard 12 is a guideway 22 in which is mounted for reciprocating movement a fluid pressure cylinder 24 provided with a piston 26 and carrying at its lower end a hollow punch or die 28. Suitably and preferably adjustably mounted on base 10 is a second hollow punch or die 30 in co-operative relation to the die 28.

To reciprocate the cylinder 24 and die 28 so as to bring the two dies into co-operative relation, there is mounted upon the drive shaft 16 a cam 40 contacting with a pair of opposed bearing surfaces 42 and 44 of a reciprocal member 46 connected at one end 106 to the cylinder 24 and having a sliding bearing at the other end at 48, whereby rotation of the cam 40 in the direction of the arrow in Fig. 2 will move the punch 28 into and out of co-operative relation to the punch 30. 110

The movement of the punch 28 is so regulated that the two dies never come quite into contact, they being so set as to come within such a distance of one another as to cut ⁸ nearly but not quite through the stock operated upon.

As illustrated in Fig. 4 the edge of the lower die is formed at a more acute angle than that of the upper die so that the former ¹⁰ will begin to cut the stock sooner than the latter, the idea being to compress somewhat the pill and to exert a downward pressure on it by the upper die. The pill thus partially formed is then forced from the stock ¹⁵ by fluid pressure produced by the descent of the piston 26.

In the illustrated machine the cam 40 is provided with a crank pin 50 which is received by a bearing carried by the piston rod 52, the latter preferably being adjustable as to its length so that the pressure may be varied to suit different conditions of operation. The form and position of the cam 40 and its relation to the crank pin 50 ²⁰ are such that there is little compression of the air in the cylinder at the start of the cut but at the completion of the cut the pressure of the air in the cylinder is at a maximum so that when the die 28 reaches its ²⁵ lowest position the pill will be forced from the stock and out through the die 30 by the pressure of the air in the cylinder.

Where in this specification the terms "upper" or "lower" die or punch occur, it is to be understood that these terms are used for purposes of convenience in referring to the accompanying drawings and that so far as various aspects of the invention are concerned it is entirely immaterial which die is ³⁰ above and which is below or indeed whether either is above the other, the relative position of the two being the thing that it is intended to emphasize.

Having described my invention, what I ⁴⁵ claim as new and desire to secure by Letters Patent of the United States is:

1. That improvement in perforating which consists in partially severing a pill from a piece of stock by making a ring-like ⁵⁰ incision and completing the severing from the stock of the pill thus partially formed by a force applied to the surface of the pill inside said incision.

2. That improvement in perforating ⁵⁵ which consists in partially severing a pill from a piece of stock and completing the severing of the pill thus partially formed by blowing it from the stock.

3. That improvement in perforating ⁶⁰ which consists in positioning a piece of stock to be perforated between a pair of hollow dies, relatively moving said dies so as to cut into the stock from both sides without completely severing the pill thus formed, and completing the severing of the pill by pres-

sure exerted through the opening in one of the hollow dies.

4. That improvement in perforating which consists in supporting a piece of stock around an opening, cutting into the stock ⁷⁰ in a closed path nearly as far as the outline of the opening, and completing the separation of the partially formed pill by blowing it from the stock and through the opening.

5. That improvement in perforating ⁷⁵ which consists in cutting a piece of stock so as almost to sever a pill therefrom, and completing the severing of the pill from the stock by fluid pressure.

6. That improvement in perforating ⁸⁰ which consists in partially severing a pill from a piece of stock with a hollow tool and completing the severing from the stock of the pill thus partially formed by fluid pressure exerted through the opening in the hollow tool. ⁸⁵

7. That improvement in perforating which consists in positioning a piece of stock to be perforated between a pair of hollow dies, relatively moving said dies in a direction to perforate the stock, and passing a fluid current through the opening in one of the dies to force out the pill through the other die. ⁹⁰

8. That improvement in perforating ⁹⁵ which consists in positioning a piece of stock to be perforated between a pair of hollow dies, relatively moving said dies so as almost to sever a pill from the stock, and completing the severing of the pill from the ¹⁰⁰ stock by fluid pressure exerted through the opening in one of the hollow dies.

9. That improvement in perforating which consists in positioning a piece of stock to be perforated between a pair of hollow dies, relatively moving said dies so as to cut ¹⁰⁵ into the stock from both sides and forcing the pill thus formed from the stock through the opening in one of the dies by fluid pressure exerted through the other die. ¹¹⁰

10. In a perforating machine, the combination of means partially to sever a pill from a piece of stock by making a ring-like incision, and means constructed and arranged to apply a tearing force wholly within the incision to the surface of the pill thus partially formed to push it out of the piece of stock. ¹¹⁵

11. In a perforating machine, the combination of a hollow punch, means relatively to move said punch and a piece of stock to be perforated to cause the punch to cut part way through the stock, and means acting through the opening in said hollow punch to sever completely the pill thus partially formed from the stock. ¹²⁰

12. In a perforating machine, the combination of a pair of hollow dies, means for moving one of the dies towards the other to penetrate, without severing, a piece of stock, ¹²⁵

and a fluid pump communicating with one of said dies for tearing the partly severed pill from the rest of the stock.

13. In a perforating machine, the combination of a hollow punch, means relatively to move said punch and a piece of stock to be perforated to cause the punch to cut the stock, and a source of fluid pressure in communication with said punch to force the pill 70 cut by the punch from the stock.

14. In a perforating machine, the combination of a pair of co-operating dies, means arranged relatively to reciprocate said dies so as to cut into a piece of stock supported 75 therebetween without bringing the dies of the pair into contact, and means for moving a fluid current through the dies to sever completely the part of the stock between the dies.

15. In a perforating machine, the combination of a pair of co-operating dies of equal area, means arranged relatively to reciprocate said dies so as to cut from both sides into a piece of stock held therebetween 80 without bringing the dies of the pair into contact, and fluid means for severing the partially cut pill from the stock.

16. In a perforating machine, the combination of a pair of hollow dies, means arranged relatively to reciprocate said dies so as to cut nearly through a piece of stock held therebetween, and means to apply 85 fluid pressure to the stock through the opening in one of the dies to force the pill out through the other die.

17. In a perforating machine, the combination of a fluid pressure cylinder, a hollow die carried by said cylinder and in communication with the interior thereof, and a piston 90 ton in co-operative relation to said cylinder.

18. In a perforating machine, the combination of a fluid pressure cylinder, a hollow die carried by said cylinder and in communication with the interior thereof, a piston 95 ton in co-operative relation to said cylinder, means to reciprocate said die and cylinder to perforate a piece of stock, and means to reciprocate said piston in timed relation to the reciprocation of said die and cylinder to force from the stock the pills cut by said die.

19. In a perforating machine, the combination of a pair of hollow dies, means relatively to reciprocate said dies to cut a piece 100 of stock held therebetween, and means to apply fluid pressure through the opening in one of the dies to force the pills cut by the dies out through the other die.

20. In a perforating machine, the combination of a pair of co-operating hollow dies, one of said dies having a cutting edge formed at a more acute angle than that of the other, and means relatively to reciprocate said dies.

21. In a perforating machine, the combination of a pair of hollow dies, one of said dies having a cutting edge formed at a more acute angle than that of the other, and means relatively to reciprocate said dies to bring their cutting edges nearly but not quite into contact whereby the die having its cutting edge formed at the more acute angle will first begin to cut stock positioned between them and the die having its edge formed at the less acute angle will later begin to cut the stock and will compress the pill thereby formed and tend to force it through the other die.

22. In a perforating machine, the combination of a pair of hollow dies, one of said dies having a cutting edge formed at a more acute angle than that of the other, means relatively to reciprocate said dies partially to perforate stock positioned between them, and means to force from the stock the pills thus partially formed.

23. In a perforating machine, the combination of a pair of hollow dies, one of said dies having a cutting edge formed at a more acute angle than that of the other, and a source of fluid pressure in communication with the die having its cutting edge formed at the less acute angle to force the pills cut by the dies out through the die having its cutting edge formed at the more acute angle.

24. In a perforating machine, the combination of a source of fluid pressure having as elements thereof a cylinder and piston, a hollow punch carried by one of said elements and having communication with the interior of the cylinder, means relatively to reciprocate stock to be perforated and the punch to cut the stock, and means to reciprocate the other said element in timed relation to said first named reciprocation to force from the stock the pill cut by said punch.

25. In a perforating machine, the combination of a pair of co-operating hollow dies, a fluid pressure cylinder carrying one of said dies in communication with the interior thereof, means relatively to reciprocate said dies to perforate stock held therebetween, a piston in co-operative relation to said cylinder, and means to reciprocate said piston in timed relation to the relative reciprocation of said dies to force from the stock the pills cut by the dies.

26. In a perforating machine, the combination of a hollow die, a member co-operating therewith to perforate stock by the relative reciprocation of said die and said member, said member having a hole therein in opposed relation to said die and a source of fluid pressure in communication with said hole.

27. In a perforating machine, the combination of a hollow die, a member co-operating therewith to perforate stock by the relative reciprocation of said die and said member, said member having a hole therein.

- in opposed relation to said die, and a fluid pressure cylinder and piston in communication with said hole to force the pill cut from the stock out through said die.
5. 28. In a perforating machine, the combination of a fluid pressure cylinder, a perforating element carried thereby and having a hole in communication with the interior of the cylinder, a piston in co-operative relation to said cylinder, a cam for reciprocating said cylinder, and a crank for reciprocating said piston in timed relation to the reciprocation of said cylinder to force from the stock the pills cut by the reciprocation of said perforating element.
- 10
15
- In testimony whereof I have signed my name to this specification.

BERNARD T. LEVEQUE.
